UNITED STATES PATENT OFFICE.

WALDO J. GUILD, OF WORCESTER, MASSACHUSETTS, ASSIGNOR TO THE HEALD MACHINE COMPANY, OF WORCESTER, MASSACHUSETTS, A CORPORATION OF MASSACHUSETTS.

GRINDING MACHINE.

Application filed August 7, 1925. Serial No. 48,734.

The present invention relates to grinding machines. In certain of its aspects it is applicable to any of the various types of grinding machines, but its particular utility is in connection with internal grinding machines for grinding the internal cylindrical or conical surfaces of sleeves, gears, bushings, ball races and like articles.

The general object of the invention is to provide a machine of this class that is capable of rapid and efficient production of such articles, ground and finished uniformly to within the closest limits of the desired and predetermined diameters. More specifically, the invention provides a machine which entirely eliminates the necessity for interruptions of the grinding by the operator, which interruptions have heretofore been frequent, for the operator to plug or gauge the work as it approaches finished size. The machine is so organized that, in the grinding of each piece of work, there occurs, automatically firstly, the dressing or truing of the grinding wheel, so that the final and finishing cuts which bring the work to the desired size are always taken with a fresh cutting surface that is straight and true, for the production of a smooth truly cylindrical hole, and secondly, the automatic cessation of grinding, when the workpiece comes to size.

In accomplishing these and other objects of the invention, certain of the mechanisms shown and described in the copending application of Heald, Guild, Burns and Garno, Serial No. 4,466, and to a certain extent those shown in the copending application of Kempston and Gallimore, Serial No. 6,689, are employed. In the machine of said copending application, the automatic operations above referred to are made responsive to a work-caliper device, which is maintained in contact with the surface that is being ground; in the machine of the present invention however, the said automatic operations, namely the dressing or truing of the grinding wheel, followed by the resumption and then the subsequent cessation of the grinding, are obtained in response to predetermined movements of the cross-feed mechanism of the machine, i. e., the mechanism by which the work and the grinding wheel are progressively fed toward each other, crosswise of the machine. In this way, the machine is enabled to handle work-pieces having non-continuous interior sur-

faces, i. e., holes with key-ways, and the like, which would not be possible when using the work-caliper device above referred to.

The above and other objects of the invention will appear from the following detailed description, taken in connection with the accompanying drawings, in which—

Fig. 1 is a front elevation illustrating an internal grinding machine to which my invention is applied.

Fig. 2 is a front view, on a larger scale, illustrating the cross-feed mechanism of said machine.

Fig. 3 is a top plan view of the parts shown in Fig. 2.

Fig. 4 is a sectional view on the line 4—4 of Fig. 3.

Figs. 5 and 6 are fragmentary sectional views, on an enlarged scale, taken, respectively, on the lines 5—5 and 6—6 of Fig. 4.

Fig. 7 is a view similar to Fig. 4, showing a modification in the construction of the cross-feed mechanism.

Fig. 8 is a section on the line 8—8 of Fig. 7.

Fig. 9 is a fragmentary sectional view on the line 9—9 of Fig. 7.

Fig. 10 is a wiring diagram of the electrical parts and connections used in the machine.

Like reference characters refer to like parts in the different figures.

Referring first to Fig. 1, the machine provides the usual reciprocating table or carriage 1 which is ordinarily provided in any internal grinding machine. In such a machine either the grinding wheel or the work to be ground may be carried on the table 1, the reciprocation of the latter being utilized in either case to produce a relative traversing movement between the grinding wheel and the work. As here shown, the table 1 supports and carries a wheel head 2, while the work which is to be operated upon is held in a work head 3, the latter being carried by a bridge 4, which spans the slideways provided by the machine frame for the back and forth movement of the table 1.

This back and forth movement of the table 1 to cause the rotating grinding wheel 5 to make the required interior traverse of the rotating workpiece 6 may be imparted in any well known manner, as for instance, by the use of the fluid pressure controlling and reversing mechanism which forms the subject

matter of the copending application of Heald and Guild, Serial No. 629,882, filed April 4, 1923, now Patent No. 1,582,468, granted April 27, 1926. Such mechanism, or its equivalent, forms no part of the present invention, and a detailed description thereof is therefore unnecessary; it is sufficient to note for the purposes of the present application, that the driving means employed for the reciprocation of the table 1, be it hydraulic drive, or gear drive, or any other type, procures the reversal of said table at each end of the latter's normal working stroke by the use of spaced adjustable dogs 7 and 8, carried by the table 1 and adapted to alternately engage and move a reversing member 9; the latter, during the grinding operation, when the wheel 5 is moving back and forth within the work-piece 6, is situated between the two dogs 7 and 8 in position to be struck alternately by said dogs, and by its consequent movement, first in one way and then the other, effects the reversals in the travel of table 1. In the machine herein illustrated, the grinding wheel 5 is rotated at high speed in any suitable manner, as for instance, by a belt drive for the wheel spindle 10, the latter for this purpose carrying a pulley 10^a. The work-piece 6 is also rotated, but at a slower speed, this rotation being imparted in any suitable manner as by a belt drive, not shown, from a countershaft.

The above described mechanism is all old and well known in the art and of itself forms no part of the present invention. The latter involves the attainment, in connection with such or similar grinding machine instrumentalities, of the novel and useful objects and results hereinbefore set forth, which are initiated by and under the control of the cross-feed mechanism of the machine, as disclosed in the form shown by Figs. 2 to 6 inclusive, or in the form shown by Figs. 7 to 9 inclusive. In the present machine, the cross-feed between work and grinding wheel is obtained by moving the wheel head 2 transversely of the reciprocating table 1, but obviously, the invention is not limited in this respect, since the cross-feed mechanism, as hereinabove described, might as readily be applied to the transverse movement of the work head 3.

The wheel head 2 of the machine is mounted on a cross-slide 11, the latter adapted to have an in and out movement on suitable ways 12 provided by a standard or bracket 13, Fig. 2, on the reciprocating table 1. Movement of said cross-slide 11 is secured by rotation of a screw shaft 14, the latter engaging an internally threaded member 15, Fig. 4, which is secured in any suitable way to the slide 11. The screw shaft 14 is journaled in a stationary sleeve 16, the latter being carried by a forward portion 17 of the bracket 13 or standard 13. Any suitable means may be

provided for preventing endwise movement of the screw shaft 14, as for instance, ball thrust bearings 18, 18 cooperating with a shouldered portion 19 of said screw shaft. Rotation of said screw shaft, to procure the in or out movement of slide 11, is effected in the following manner:—

In the form of cross-feed mechanism shown in Figs. 2—6 inclusive, and referring particularly to Fig. 4, a sleeve 20 is suitably secured, by a key 21, or the like, to the outer end of screw shaft 14, and on this sleeve is rotatably mounted a member 22, hereinafter called a drive ring. Projecting inwardly from drive ring 22 is a stud 23, having journaled thereon the integrally united spur gears 24 and 25, the larger of which, 24, is in mesh with stationary spur gear teeth 26 formed on the sleeve 16, while the smaller of which, 25, is in mesh with spur gear teeth 27 formed on the sleeve 20. The drive ring 22 is subject to rotation, either by hand or automatically, as hereinafter described, and when such rotation is imparted, the gear 24, carried thereby around the stationary gear 26, is rotated on its own axis provided by the stud 23. This last named rotation, in which the gear 25 also participates, is transmitted by said last named gear, in mesh with the teeth 27, to the sleeve 20, thus to impart rotation to the screw shaft 14, but at an angular speed very much reduced from that imparted to the drive ring 22.

The manual rotation of the drive ring 22 is effected by a hand wheel 28, the latter, as shown in Fig. 4, being integrally connected by a plurality of ribs 29 with an annular hub 30, which is journaled and turns freely on the outer periphery of the drive ring 22. Provision is made in the form of a screw 31 for temporarily locking the hub 30 and drive ring 22 for rotation in unison, and it will be understood that under these conditions, the clockwise rotation of hand wheel 28 will procure an inward feed of the grinding wheel 5 toward the surface being ground, while a counterclockwise rotation of said hand wheel will procure a reverse movement of said grinding wheel, said movements in either case being effected by rotation of the screw shaft 14 as imparted by the reduction gearing above described between said screw shaft and the drive ring. In the ordinary operation of the machine however, the screw 31, as hereinabove described, is retracted from contact with the periphery of drive ring 22, leaving the hub 30 of hand wheel 28 free to rotate on said periphery, and other means are provided, as will now be described, for imparting the rotation of said hand wheel to said drive ring.

Immediately adjacent the inner face of hub 30 is disposed an annular member 32, hereinafter called the dial ring, this member having secured thereto in any suitable manner,

as by a pin 33, a ratchet ring 34, which finds journal bearing on an inward extension 35 of the drive ring 22. Said ratchet ring 34 is the means by which the usual automatic inward feed of the grinding wheel 5, in response to the back and forth longitudinal traversing movements of said wheel, is imparted. To this end there is pivoted at 36 on the forward portion 17 of bracket 13 a member 37, Figs. 2 and 3, carrying a pawl 38 adapted to engage the teeth of ratchet ring 34, to rotate said ring and with it the dial ring 32, in a clockwise direction. A roller 39 carried by member 37 is adapted, at the 15 end of each left hand longitudinal stroke of the table 1, to engage a stationary cam 40, Fig. 1, which is carried by a suitable bracket 41 rising from the machine frame, said cam 40 being longitudinally adjustable on said bracket so that it can be set to be engaged by the roller 39 at the proper time. When said roller 39 engages the cam 40, the member 37 is rocked upwardly, thereby causing the pawl 38 to operatively engage and move 20 the ratchet ring 34; in the operation of the machine, this produces a step-by-step clockwise rotation of said ratchet ring together with its attached dial ring 32, and this rotation is communicated through the drive ring 22 to the screw shaft 14 in the following manner:—

The dial ring 32, as shown in Figs. 4 and 5, carries a spring pressed member 42, which acts as a pawl in cooperation with ratchet teeth 43 on the outer periphery of the drive ring 22. Thus, through this pawl and ratchet drive, any clockwise rotation imparted to the dial ring 32 is transmitted to the drive ring 22, and such clockwise rotation of the latter 25 secures, through the reduction gearing above described, the rotation of the screw shaft 14 in a direction to move the slide 11 inwardly, thus to feed the grinding wheel 5 toward the surface being ground. The pawl and ratchet drive 42, 43 permits said dial ring 32 to be turned counterclockwise by said hand wheel, as hereinafter described, without transmitting its rotation to the drive ring 22. Before describing in detail the use of said hand wheel 30 28 in connection with the respective rings 22 and 32, the cooperation of the cross-fed mechanism with the various automatic instrumentalities of the machine will be fully set forth.

As shown in Figs. 3, 4 and 10, the dial ring 32 carries a cam projection 44 which, in the clockwise rotation of said dial ring, is adapted to engage successively with two adjustable screws 45 and 49. The screw 45 is carried 35 by a pivoted member 46, and the rocking of said member 46, under the influence of said cam 44, causes the engagement of two electrical contacts 47 and 48, Fig. 10. The screw 49 is carried by a pivoted member 50, and 40 the rocking of said member, under the influ-

ence of said cam 44, causes the engagement of two electrical contacts 51 and 52, Fig. 10. As hereinafter described, engagement of the contacts 47 and 48 causes the wheel dressing instrumentalities of the machine to be 70 brought into operation, while engagement of the contacts 51 and 52 causes longitudinal separation of the grinding wheel 5 from the workpiece 6, the former being moved to its extreme right hand position, as shown in 75 Fig. 1.

When the terminals 47 and 48 make contact, an electrical circuit is formed which, by the mechanism to be presently described, causes the table 1 to have an amplified stroke 80 to the right, in order to withdraw the grinding wheel 5 from the work, and simultaneously causes a wheel dressing member or diamond 53 to move into the amplified path of said grinding wheel, thereby to true the periphery of the latter as it passes the point of said diamond. As shown by the wiring diagram of Fig. 10, electrical current may be supplied by a direct current generator 54 driven continuously by any suitable means, 85 not shown, from the same source of power that is used for the rotation of the grinding wheel or the work spindle. One terminal of this generator 54 is grounded, as shown at 55, and the other is connected by a supply lead 90 56 to the central bar or plate 57 of a two-way switch,—the latter being designated as a whole by the numeral 58 and being disposed, as shown in Fig. 1, on the front of the machine. Said switch 58 provides additional 100 contact plates or bars 59 and 60 arranged on opposite sides of the central bar 57 and adapted to be alternately connected electrically to said central bar 57 by a connector 61, which is mounted on an oscillatory member 105 62. The latter is pivoted at 63 and in its normal position, as shown in Fig. 10, disposes the connector 61 in contact with and across the two plates 57 and 59; in the other position of movable member 62, the connector 61 110 connects the two plates 57 and 60.

The normal position of movable switch member 62 is that shown in Fig. 10, and under these conditions, the supply lead 56 from the generator 54 is connected to a lead 115 64 taken off of the plate or bar 59 of the switch 58. Said lead 64 runs to the coil of an electromagnet 65 disposed in the front of the machine, shown in Figs. 1 and 10. A return lead 66 from the coil of the electromagnet 65 is connected to a finger 67 provided on any convenient stationary portion of the machine frame. A brush or plate 68 is carried by the table 1, and during the normal working traverse of the table 1, when the grinding wheel 5 is moving back and forth within the workpiece, the finger 67 is in contact with the brush or plate 68. The latter is connected by a lead 68^a to the contact terminal 48. When the terminals 47 and 48 are 120 125 130

- brought together as above described, by the action of cam 44, the circuit through electromagnet 65 is completed, since the terminal 47 is grounded, as shown at 47^a, Fig. 10. 8
- 8 This energizes the electromagnet 65, causing attraction of an armature member 69, and the consequent elevation of its attached lever arm 70, these parts being pivoted at 71 on the front of the machine. Such movement of 10 the lever arm 70, responsive to the engagement of cam 44 with screw 45, is made use of to automatically interrupt the grinding operation on the workpiece 6 for the dressing and truing of the grinding wheel 5, in 15 advance of the final and finishing cuts taken by said wheel to bring the workpiece to the desired size. This involves the withdrawal of the grinding wheel 5 from the workpiece, and the disposal, in the temporarily amplified path of movement of said wheel of the dressing device or diamond 53; these two operations are effected through the medium of the lever arm 70 in the following manner:—
- 20 As fully described in the copending application of Heald and Guild, Serial No. 25,900, filed April 25, 1925, the dressing device 53 may be moved into operative position through the medium of fluid under pressure, 25 more especially when such pressure fluid is employed for imparting reciprocation to the table 1. The means by which said pressure fluid is made available for the movement of dressing device 53 into operative position 30 forms, of itself, no part of the present invention, being fully described and claimed in the aforesaid application of Heald and Guild, Serial No. 25,900; it is sufficient to note, for purposes of this application, that, as described in said Heald and Guild application, the dresser point 53, suitably mounted on an adjustable screw plug 72, is lowered into operative position by the downward swinging movement of a carrying member 73, 35 which turns on a trunnion 74 provided by a suitable standard 75 rising from the stationary frame of the machine. When the lever arm 70 is moved, a downward extension 76 thereof communicates said movement to a 40 valve 77, Fig. 1, thus making the pressure fluid active, through suitable connections, against a piston, not shown, which is operatively associated with the member 73, thereby to swing the dresser point 53 from the in- 45 operative position, that it normally occupies, down into its operative position in the path of grinding wheel 5. A handle 78 is also provided for this same purpose, for use when the member 73 is disconnected from the fluid 50 pressure operating devices. My invention, of course, is not limited to the above described use of pressure fluid for disposing the dresser 53 in operative position; obviously, any other type of dresser moving 55 mechanism, such as that disclosed in the co-

pending application of Heald, Guild, Burns and Garno, Serial No. 4,466, filed January 24, 1925, may be made responsive to the engagement of cam 44 with screw 45.

As before stated, the other operation inaugurated by said engagement is the automatic amplification of the reciprocatory path of table 1, to carry the wheel 5 past the dresser 53. As shown in Fig. 1, the left hand table dog 8, which limits the right hand movement of table 1, is carried by a block 79, which instead of being secured directly to the table 1 as in the case with the block 80 of dog 7, is mounted so as to be capable of sliding freely longitudinally of said table. 75 Under normal conditions, when the table is making its usual working reciprocations to traverse the grinding wheel 5 back and forth within the workpiece, the block 79 of dog 8 is held in definite spaced relation to a block 81, which latter, the same as the block 80 of right hand dog 7, is a stationary block adapted to maintain its predetermined setting or adjustment longitudinally of the table 1, as given it by any suitable adjustment or holding devices, such for instance, as the hand screw nuts 82, 82 applied to both blocks 80 and 81 and engaging with the screw rack 83 on the table 1.

The device employed to hold the slidable block 79 in spaced relation to the fixed block 81 is here shown as a latch lever 84 pivoted at 85 on block 81, and having its free end disposed by gravity in abutting relation to a shoulder 86 on block 79, thereby holding the block 79 at a predetermined distance to the right of block 81. When the latch member 84 is lifted to free its end from the shoulder 86, the normal connection between the slid- 10 able block 79 and the fixed block 81 is broken, and when this occurs on the right hand movement of table 1, the dog 8 will bear without effect against the member 9. Thus the right hand movement of the table 1 on this particular stroke will be extended beyond the 11 usual reciprocatory working path, and the grinding wheel 5 will be carried out of the hole in the workpiece to a point just beyond that occupied by the dressing device, which latter, as already described, has been moved 12 into operative position as the amplified right hand travel of table 1 begins. This amplified right hand travel of table 1 involves relative sliding movement between said table and the block 79, owing to the obstruction which the reversing member 9 imposes against the dog 8 to prevent the block 79 from moving with the table; finally, the block 79 brings up against the block 81, whereupon the solid backing thus afforded for the block 79 enables the dog 8 to shift the member 9. This procures reversal of the table 1, and the left hand movement of said table thus inaugurated is caused to restore the parts automatically to normal position in the following manner: 13

A member 87 pivotally mounted on the frame of the machine has a pair of inclined surfaces 88 and 89 for cooperation, respectively, with inclined surfaces 90 and 91 at the lower corners of the block 79. A spring 92 presses said member 87 upwardly. In the normal grinding operation of the machine when the blocks 79 and 81 are connected by latch 84, the surfaces 88 and 89, although in the path of block 79, offer no effective obstruction to the back and forth travel of said block in unison with the table 1, it being obvious that when either lower corner of the block under these conditions strikes either of the bevelled surfaces 90 or 91, such contact will wedge the spring 92 downwardly, said spring yielding sufficiently to allow the block 79 to pass over the member 74. However, when the block 79 has been freed from the block 81 as above described, to amplify a single right hand stroke of the table 1, the ensuing reversal of said table, with the block 79 still free, finds the surface 88 in position to contact with the corner 90 of said block, and under these conditions, the obstruction offered is sufficient to overcome whatever friction there may be tending to cause the block 79 to move to the left with the table. The block 79 being thus held stationary while the table 1 and block 81 continue to move to the left, the latch member 84 finally resumes its normal position relative to the block 79, the end of said latch member dropping behind the shoulder 86 and the parts being thus automatically restored to normal position at the conclusion of each single amplified reciprocation of the table 1.

Said single amplified reciprocation of the table 1 for wheel dressing purposes is, in the present invention, inaugurated automatically upon a predetermined preliminary amount of grinding having been done on each workpiece, by the making of electrical contacts through the terminals 47 and 48 as already described, thus moving the lever 70 about its pivot 71. The lever 70 has a roller 93 on the upper portion thereof, and upon movement of this lever during normal working traverse of the grinding wheel 5, the roller 93 engages and lifts the latch lever 84, thus causing the above described amplified movement of the table 1, which carries the grinding wheel 5 to the right, past the diamond 53, and then to the left, again passing said diamond before resuming the normal reciprocatory traverse of the workpiece 6. Thereupon, by any suitable means, such as that shown and described in the aforesaid copending application of Heald and Guild, the diamond 53 is rocked upwardly into the inoperative position that it normally occupies.

On this amplified right hand dressing stroke of the table 1, an arm 94, Fig. 1, pivoted at 85 and hanging by gravity in the position shown in Fig. 1, strikes an arm 95,

Fig. 10, of movable switch member 62, thereby rocking said switch member away from bar 59, which prevents a repetition of the dressing stroke. Thereupon the connector 61 is disposed in position to connect the switch plates or bars 57 and 60. A lead 96 runs from the switch bar 60 to the coil of a second electromagnet 97, and the other end of said coil is connected by a lead 98 to a finger 99 carried by the machine frame preferably adjacent to the finger 67. Said finger 99 makes contact with a brush or plate 100, carried by the table 1 adjacent to the plate 68, and a lead 101 connects the plate 100 with the contact 52.

After the wheel dressing operation above described, and with the resumption of grinding upon the workpiece 6, the inward feeding of the grinding wheel 5 involves further clockwise rotation of the dial ring 32, which ultimately carries the cam 44 into engagement with the screw 49. The parts are so set and adjusted, as hereinafter described, that this engagement takes place just as the workpiece 6 reaches the exact desired size; the consequent rocking of member 50 brings together the contacts 51 and 52 and completes the electrical circuit through the magnet 97, since the contact 51 is grounded, the same as the contact 47, at 47°. Thus the electromagnet 97 is energized, causing attraction of an armature member 102 pivoted, as shown in Fig. 1, on the same spindle 71 which forms the pivot for the armature member 69. The armature member 102 provides a lever arm 103 for cooperation with the left hand table dog 8 in the following manner:

Said table dog 8, as shown in Fig. 1, is pivoted at 104 to its carrying block 79, and normally rests by gravity against a pin 105, thereby to maintain its free end in position to engage and move the reversing member 9 at the end of the right hand normal working stroke of the table 1. When the magnet 97, in response to the grinding of the workpiece to the exact desired size, is energized, the lever arm 103 is raised into the path of dog 8, and the latter, on the right hand movement of table 1, by reason of its pivotal mounting, is free to ride on the upper surface of said lever arm; thus the striking end of said dog 8 is carried clear of the reversing member 9, and the table 1 continues its movement to the right, carrying the grinding wheel 5 out of the workpiece and well past the then inoperative dressing device 53, said table ultimately carrying the grinding wheel 5 into the position illustrated in Fig. 1, and there being brought to a full stop by any suitable means, such for example, as those shown in the aforesaid copending application of Heald and Guild, Serial No. 629,882. Thus with the coming to size of a given workpiece 6, the mechanism automatically secures the complete cessation of the grinding operation, and the full longitudinal separation of the

grinding wheel from the workpiece, permitting full access to said workpiece for its removal from the machine, and the insertion in said machine of a new unground workpiece 5 while the grinding wheel 5 is entirely out of the way.

The return to working position, from the full withdrawal position shown in Fig. 1, is effected by the shifting of a hand lever 106, 10 operatively connected to the reversing member 9 and adapted to throw said reversing member to the right, thereby to inaugurate a left hand movement of the table 1. On this left hand movement, an arm 107, pivoted 15 at 85 and hanging by gravity in the position shown in Fig. 1, strikes an arm 108 of movable switch member 62, thereby rocking said switch member so that its connector 61 is returned to the position shown in Fig. 10, 20 in readiness for the energization, at the proper time in the grinding of the next workpiece, of the electromagnet 65 which inaugurates, as above described, the wheel dressing operation. As shown in Fig. 1, and as described in the aforesaid copending application of Heald, Guild, Burns and Garno, the arms 95 and 108 of movable switch member 62 are offset from one another, as are also 25 the corresponding striking arms 94 and 107, respectively, of the table 1. As the table travels to the left to resume a working position, the dog 8, upon engagement with the member 9, yields upwardly and then, after 30 passing over said member 9, drops by gravity 35 into its usual position, so that said member 9 thereafter is disposed between the striking faces of the dogs 7 and 8.

The quantity production of identical workpieces all ground to the same exact internal size, involves a predetermined setting of the cross-feed mechanism above described, by the aid of a sample workpiece or pattern, which is first ground to exact size in any suitable way, as by the use of ordinary sizing plugs or 40 gauges. In the production of this sample workpiece, the various electrical and other automatic devices hereinbefore referred to, are not employed, and the cross-feed of the grinding wheel is preferably effected by hand, 45 the hand wheel 28 for this purpose being secured, by screw 31, to the drive ring 22, Fig. 4. When the sample workpiece has been 50 ground to the exact desired size, the cross-feed of the wheel 5 is discontinued, and the table 1 is then actuated to withdraw the grinding wheel from the workpiece and to dispose 55 said wheel substantially in the dressing position; this may be done by lifting the latch lever 84 manually and by shutting off the supply 60 of pressure fluid to stop the movement of the table when the latter reaches the desired position. Thereupon, the cross slide 11 being then in the precise position which secures the 65 grinding of said workpiece to the desired inter-¹ diameter, the parts, without disturb-

ing the position of said cross slide, are set so that the cam 44 on the dial ring 32 will just bring the contacts 51 and 52 together, this position signifying the cessation of the grinding operation by energization of the 7¹ magnet 97, as above described. This setting of the dial ring 32 is accomplished by manually turning the dial ring counterclockwise, an action which is permitted to take place without any turning of the drive ring 22, 75 since the pawl and ratchet drive 42, 43 between said rings only works in a clockwise direction. In this position of engagement between cam 44 and screw 49, which causes the contacts 51 and 52 to come together, a 80 mark or pointer 109, Fig. 3, on a member 110, carried by bracket extension 17, always registers with a zero marking 111 of the dial ring 32.

The next step in the setting of the parts is 85 to turn the dial ring 32, through the hand wheel 28, backward or counterclockwise from this zero position through a selected number of dial ring indications, which may conveniently represent thousandths of an inch, the 90 number of such graduations representing the distance by which the operator desires the automatic wheel dressing operation to precede the attainment of finished size by the workpiece; in this position of the dial ring, the screw 45 is adjusted so that its engagement by cam 44 will just bring the contacts 47 and 48 together. The backward setting of the dial ring 32 to this point, which signifies the inauguration of the wheel dressing operation, by 95 energization of the electromagnet 65, should be accompanied by a corresponding movement of retraction of the cross slide 11, and this in turn involves a counterclockwise rotation of the drive ring 22 in unison with the dial ring 100 : 32. To secure this operation, the mechanism provides a pawl and ratchet drive between the hub 30 of hand wheel 28 and the adjacent face of dial ring 32, consisting of ratchet teeth 112 formed on the face of said dial ring, for co- 105 operation with a spring pressed member 113 contained in a recess of said hub 30, as shown in Fig. 6, and adapted to operatively engage said teeth 112 when the hand wheel 28 is 110 rotated counterclockwise. Therefore, when the screw 31 is tightened, to unite the hand wheel 28 and the drive ring 22 for rotation in unison, the counterclockwise rotation of said hand wheel, to set the cam 44 back to screw 45, 115 is accompanied by a corresponding angular movement of drive ring 22, which retracts the cross slide 11 a slight distance, thus to dispose the periphery of the grinding wheel at the point selected for the inauguration of the 120 dressing operation of said wheel.

With the grinding wheel 5 in the position above described, the dressing mechanism is adjusted so that the diamond point 53, when rocked down into operative position by the handle 78, will barely make contact with the 125

periphery of said grinding wheel; this is done tent,—in other words, at each retraction, the by adjusting the standard 75, or by adjusting cam 44 is set back with reference to the drive screw 72, as required,—and then the parts of the dresser mechanism are fixed in this position and require no further adjustment. It will thus be seen that in the grinding of a subsequent workpiece, the above described setting of cam 44 with relation to screw 45 will cause the grinding operation to be interrupted when the contacts 47 and 48 are brought together, the grinding wheel 5 being then subjected automatically to the dressing operation heretofore described, following which the grinding operation is automatically resumed to bring the work to the desired finished size.

The settings of the cross-feed and contact mechanisms above described are adapted for the production, by the machine, of any desired number of pieces, corresponding to the sample workpiece and ground internally to the same diameter,—it being understood, of course, that with each successive workpiece introduced to the machine, the grinding wheel 5 is fed inwardly automatically by the pawl 25 and ratchet drive 38, 34 for the dial ring 32, whose clockwise rotation is in turn imparted to the drive ring 22 by the pawl and ratchet drive 42, 48.

At the finish of the grinding operation on each workpiece, it is necessary, of course, to retract the cross slide 11 by hand, in order that the grinding wheel 5 may be in position to enter the unground hole in the next workpiece, without striking the edge of said hole. It will readily be seen that if the counterclockwise rotation of drive ring 22 required for this retraction is accompanied by a similar rotation of cam 44, no greater in angular extent, then said cam, in the grinding of the new workpiece, will cause the contacts 47 and 48 to come together prematurely, inasmuch as the grinding wheel 5, having been reduced in diameter by the dressing operation taking place during the grinding of the preceding workpiece, as well as by inevitable wear thereon in the grinding done by it since said dressing, will not make contact peripherally with the dresser point 53. In like manner also, under the conditions assumed, the bringing together of contacts 51 and 52 will also be premature, in consequence of which the automatic cessation of the grinding operation, brought about by the energization of electromagnet 97, will take place before the hole in the workpiece has been ground to the required diameter.

Therefore, in order to compensate for wear on the grinding wheel and also for the reduction of its diameter by dressing, means are provided whereby, at each retraction of the cross slide 11, the counterclockwise turning of the drive ring 22 to accomplish said retraction, is accompanied by a counterclockwise turning of the dial ring 32 and cam 44 which is invariably of greater angular ex-

70 produce the above described retractions of cross slide 11, carries in any suitable manner, as by means of screws 114 a block 115, the purpose of which is to adjustably support a transverse pin 116, whose ends project beyond said block. The pin 116 is threaded, and its adjustment endwise in the block 115 is secured in any suitable manner, as by a knurled nut 117 in threaded engagement with said pin and disposed in a recess of said block. The drive 80 ring 22 provides a pair of lugs 118 and 119, on opposite sides of the block 115 of the hand wheel 28, these lugs being spaced apart peripherally to provide lost motion between hand wheel 28 and drive ring 22. By clockwise 85 rotation of the hand wheel 28 relative to drive ring 22, the right hand end of pin 116 will be brought into engagement with the lug 119, and by counterclockwise rotation of said hand wheel, relative to drive ring 22, the left 90 hand side of block 115 will be brought into contact with lug 118.

During the automatic inward feed of cross slide 11, accomplished, as above described, by clockwise rotation in unison of drive ring 95 22 and dial ring 32, the hand wheel 28 also turns clockwise, because one of the ratchet teeth 112 of dial ring 32 will press operatively against the pawl 113, thereby causing the hand wheel 28 to move in unison with the dial 100 ring 32. At the finish of the grinding operation on a given workpiece, with the parts in the positions illustrated in Fig. 1, let it be assumed that the hand wheel 28 is in the position illustrated in Fig. 1, where the right 105 hand end of pin 116 bears against lug 119 of drive ring 22. For the necessary retraction of cross slide 11, before the table 1 is moved to the left to carry the grinding wheel into the new unground workpiece, the hand 110 wheel 28 is turned counterclockwise; the dial ring 32 participates in this counterclockwise rotation from its very commencement, owing to the pawl and ratchet drive 113, 112 above described, but the drive ring 22 does not begin 115 to move counterclockwise until the hand wheel 28 has been turned far enough to carry the left hand side of block 115 against the lug 118 of said drive ring. In this way the cam 44 carried by the dial ring 32 is, at each 120 retraction of the cross slide 11, turned back a definite amount in excess of the turning back of drive ring 22, this amount being the distance shown on Fig. 1 between the lug 118 and the side of block 115, and this distance being adjustable by manipulation of the knurled nut 117 to vary the right hand projection of pin 116 beyond said block, thereby to space said block more or less from the lug 119. The nut 117 should be adjusted 125

130

so that the cam 44 and the dial ring 32 will, at each such retraction of the cross slide, be turned back in excess of the retraction of the drive ring 22, by an amount which is greater than the largest estimated possible wear of the grinding wheel, because it is this excess retraction which causes the axis of the grinding wheel to be moved ever nearer to the dressing plane at each successive dressing operation, in order that contact between the wheel and dressing device may be assured. It will be understood that the operator, after retracting the cross slide 11 sufficiently by counterclockwise rotation of hand wheel 28, will then be required to turn said hand wheel clockwise through a small arc to bring the right hand end of pin 116 into contact once more with lug 119; this clockwise readjustment of the hand wheel 28 takes place without any corresponding movement of the other parts of the cross-feed mechanism, inasmuch as said hand wheel 28 is free to turn clockwise on the drive ring 22; any tendency of the drive ring 22 or dial ring 32 to follow the hand wheel 28 at this time may be overcome, if necessary, by imposition of a suitable friction or drag exerted against the drive ring, as indicated by the spring friction plug 120, Fig. 4.

From the foregoing it will be clear that with an accurate setting of the parts, as determined by the sample workpiece used as a pattern, the mechanism, operating as above described, will produce any desired number of similar workpieces, all ground internally to exactly the same diameter as the sample. This result follows from the fact that, during the final stages of grinding on each workpiece, a fixed and invariable advance of the cross slide occurs, from the time of engagement of the contacts 47 and 48 until the time of engagement of the contacts 51 and 52; inasmuch as the engagement of the contacts 47 and 48 always secures tangency between the periphery of grinding wheel 5 and a fixed vertical plane, irrespective of wear or other variable influences on said wheel, it is clear that the ensuing limited advance of the periphery of the wheel beyond said plane, being always in every case through the same distance, will result in substantially absolute uniformity of product. It will be readily understood that the machine parts should be set so that the aforesaid fixed and invariable advance of the cross slide from the dressing operation to the cessation of the grinding operation, will be greater than the amount by which the grinding wheel is reduced by dressing. If this were not so, the grinding wheel would have cut the workpiece beyond the desired finished surface prior to the engagement of the contacts 47 and 48. Such reduction of the wheel by dressing will be necessarily equal to the difference between the estimated wear of the wheel, as signified by the setting of the knurled nut 117, hereinbefore described, and the actual wear of the grinding wheel, which can only be determined by experiment. In practice, however, the operator of the machine will set the parts so that this fixed advance subsequent to dressing will be greater by a safe margin than the reduction of the wheel by dressing, which can be estimated, as indicated. Such adjustment, of course, is effected by turning of the set screws 45 and 49.

In the modified form of the cross-feed mechanism shown in Figs. 7, 8 and 9, the principle of operation is the same as above set forth, but a variation in construction, tending toward simplification, is employed. As shown in Fig. 7, a single annular member 121 combines the functions of the drive ring and the hand wheel of the previously described construction, said member having a hub portion 122, journaled on the sleeve 20 which is keyed to screw shaft 14, and said member providing the stud 23 for the support of the reduction gearing 24, 25 employed for the drive of said sleeve 20 through gear 27. Directly secured to the annular member 121 is a ratchet wheel 34^a, and the usual pawl 38, actuated as above described by the reciprocations of table 1, cooperates with said ratchet wheel to produce step-by-step clockwise rotation of member 121 for the progressive inward feed of cross slide 11.

The cam 44 in this construction is carried by a dial ring 32^a, the latter, as shown in Fig. 7, being rotatably mounted upon and supported by the annular member 121. As best shown in Fig. 9, the dial ring 32^a on its opposite sides or faces is provided with ratchet teeth 112^a, 126, the former for cooperation with a spring pressed pawl 113^a carried by the annular member 121, and the latter for cooperation with a spring pressed pawl 128 carried by another ring member 129. Said ring 129, like the dial ring 32^a, is mounted upon the annular member 121, and said ring 129 is frictionally constrained from rotation by the drag imposed by a pair of stationary spring pressed pads or shoes 130, 130, Fig. 8.

This mechanism is adapted to be adjusted and set in substantially the same manner as heretofore described for the successive engagements of cam 44 with screws 45 and 49, Fig. 10, whereby automatic dressing of the grinding wheel and subsequent automatic cessation of the grinding operation are secured. The clockwise rotation of member 121 for the inward feed of cross slide 11 is imparted to the ring 129 by a post 131, Fig. 8, projecting from member 121 and received in an elongated slot 132 of ring 129; adjustable screws 133 and 134, at the ends of said slot, are adapted to be engaged by post 131, depending upon the direction of rotation of the member 121. At the end of each grinding operation, the manner in which the cam

44 is set back, on the retraction of cross slide 11, a predetermined distance in excess of the backward feed of the other parts, is as follows:—

- 5 The member 121 is turned backward by hand to retract the cross slide, and this counterclockwise movement is imparted to the dial ring 32^a by the pawl and ratchet drive 113^a, 112^a, the parts, except ring 129, which 10 lags until post 131 picks up screw 134, moving backward in unison. Then, in the grinding of the next workpiece, the member 121 is given clockwise rotation, either by hand or by the pawl and ratchet drive 38, 34^a. However, at the commencement of this clockwise 15 rotation, the dial ring 32^a, carrying cam 44 will lag, because the pawl 128 carried by the normally stationary ring 129 will, by its engagement with one of the ratchet teeth 126, prevent clockwise rotation of the dial ring 32^a. The ring 32^a and cam 44 will be held stationary, notwithstanding the inward feed of the cross slide until the member 121 has travelled far enough to carry the post 131 into 20 contact with the screw 133 of ring 129: thereafter, the ring 129 is obliged to rotate in unison with the member 121, and this permits the dial ring 32^a and cam 44 to partake of similar clockwise movement.

- 25 In the first described form of the invention, compensation for reduction in diameter, by wear and dressing of the grinding wheel 5 is obtained, between operations on successive workpieces, in the act of retracting the cross slide 11 by the hand wheel, this imparting to the cam 44 a backward setting in excess of that imparted to the feed ratchet 34. In the second form of the invention, the same result is obtained, for the same purpose, between grinding operations on successive workpieces, when the hand wheel is turned back to retract the cross slide 11, but in this instance the cam 44 is turned back the same distance as the feed ratchet: however, the 30 cam 44 is not picked up on the ensuing inward feed of the cross slide until said inward feed has progressed a predetermined amount. It will also be noted, in this second form of the invention, that the operator is not required, after turning the hand wheel counterclockwise to retract the cross slide 11, to make any subsequent clockwise adjustment or setting of said hand wheel, as is the case with the first described form of the invention.

- 35 In both forms of the invention, the automatic wheel dressing operation takes place in advance of the final and finishing cuts which bring the workpiece to the desired finished size, and this interruption of the grinding operation on each workpiece, for the purpose of dressing the wheel, relieves the sidewise pressure of the wheel against the workpiece which has been built up in the grinding operation by successive advances of the cross-feed screw 14, and which pressure tends

sometimes to spring the wheel spindle 10, and to cause uneven wheel wear. When the grinding wheel, following its dressing, re-enters the workpiece, the cross-feed imparted to it for taking the final and finishing cuts 70 to bring the work to size, is not sufficient to build up any objectionable or excessive pressure, and hence these final and finishing cuts are taken under ideal grinding conditions. The automatic cessation of grinding, in both 75 forms of the invention, is brought about, as hereinbefore described, by a predetermined advance of the cross-slide 11 beyond the position which it occupies when the wheel dressing operation occurs; as previously described, 80 said dressing position of the cross-slide is advanced successively for each new workpiece.

I claim:

1. The combination with a grinding machine comprising means for supporting the work, means for supporting a grinding wheel, means for producing a reciprocating motion of one of said before-mentioned means with relation to the other, means to so control said motion as to cause a relative traversing motion between the wheel and the work, one past the other in contact, or to cause withdrawal of one from contact with the other and subsequent restoration to contact, a tool for dressing the grinding wheel so mounted that it is engaged by the said wheel when the contact between the work and grinding wheel has been so interrupted, and feeding mechanism that causes the grinding wheel and work to move one relative to the other transverse to said traversing motion to maintain grinding contact; of devices operated directly by said feeding mechanism and operable on said motion-controlling means to cause the withdrawal motion and then to restore the contacting traversing relation of work and grinding wheel, whereby the grinding may proceed by a succession of uninterrupted traversing motion confined to the surface to be ground, and at a stage determined directly by the movement of the feeding mechanism, the contact of grinding wheel and work is automatically interrupted, the grinding wheel is dressed and traversing contact with the work is resumed.

2. The combination with a grinding machine comprising means for supporting the work, means for supporting a grinding wheel, means for producing a reciprocating motion of one of said before-mentioned means with relation to the other, means to so control said motion as to cause a relative traversing motion between the wheel and the work, one past the other in contact, or to cause withdrawal of one from contact with the other and subsequent restoration to contact, a tool for dressing the grinding wheel so mounted that it is engaged by the said wheel when the contact between the work and grinding wheel has been so interrupted, and feeding mecha-

nism that causes the grinding wheel and work to move one relative to the other transverse to said traversing motion to maintain grinding contact; of devices operated directly by said feeding mechanism and operable on said motion-controlling means to cause the withdrawal motion and then to restore the contacting traversing relation of work and grinding wheel, and means for automatically 10 operating the feeding means during the traversing contact of the work and grinding wheel before and after the withdrawal motion, whereby the grinding may proceed by a succession of uninterrupted traversing motions confined to the surface to be ground, and at a stage determined directly by the movement of the feeding mechanism, the contact of grinding wheel and work is automatically interrupted, the grinding wheel is 20 dressed and traversing contact with the work is resumed.

3. In a grinding machine, a grinding wheel, mechanism for procuring a cross-feed between said wheel and a workpiece, means responsive to successive feeding movements of said cross-feed mechanism for procuring cessation of grinding on successive workpieces, as the latter reach a predetermined size, and means responsive to the retractile movements 30 of said cross-feed mechanism, between successive grinding operations, for compensating for the wear of said grinding wheel.

4. In a grinding machine, a grinding wheel, mechanism for procuring a cross-feed between said wheel and a workpiece, means responsive to successive feeding movements of said cross-feed mechanism for procuring a dressing operation on said grinding wheel during the grinding of each successive workpiece, and means responsive to the retractile movements of said cross-feed mechanism, between successive grinding operations, for compensating for the successive reductions in diameter of said wheel by said dressing 40 operations.

5. In a grinding machine, a grinding wheel, mechanism for procuring a cross-feed between said wheel and a workpiece, means responsive to successive feeding movements of said cross-feed mechanism, in the grinding of successive workpieces, for dressing said wheel and for procuring cessation of each successive grinding operation when the workpiece reaches a predetermined size, and means responsive to the retractile movement 50 of said cross-feed mechanism, between successive grinding operations, for compensating for the reduction in diameter of said grinding wheel, both by said dressing and by 60 wear during grinding.

6. In a grinding machine, a grinding wheel, mechanism for procuring a cross-feed between said wheel and a workpiece, means directly actuated and controlled by said cross-feed mechanism in the grinding of each work-

piece, and set in operation only after said cross-feed mechanism has caused preliminary grinding of a given workpiece, to procure a dressing operation on said grinding wheel, and means for automatically procuring cessation of the grinding operation on each workpiece upon the feeding movement of said cross-feed mechanism through a predetermined distance beyond the point where said dressing occurred. 75

7. In a cross-feed mechanism of the class described, a cross-slide, a driving member therefor, means for progressively and automatically advancing said member, a second member adapted to advance with said driving member, means operable by said second member for securing cessation of feeding movement of said cross-slide, and means automatically operated by the cross-slide operating mechanism in retracting the cross-slide 80 for setting back said second member a predetermined distance in excess of said driving member.

8. In a grinding machine, a grinding wheel, mechanism for procuring a cross-feed between said wheel and the workpiece, said mechanism comprising a cross-slide, a driving member therefor, means for progressively and automatically advancing said member, a second member adapted to advance with said driving member, means operable by said second member for securing cessation of the grinding operation by said wheel, and means automatically operated by the cross-slide operating mechanism in retracting the cross-slide, following said cessation, for setting back said second member a predetermined distance in excess of said driving member. 90

9. In a grinding machine, a grinding wheel, a wheel dressing device, mechanism for procuring a cross-feed between said wheel and the workpiece, a cross-slide forming part of said last named mechanism, a driving member for said cross-slide, means for progressively and automatically advancing said member, a second member adapted to advance with said driving member, means responsive to advancement of said second member for securing successively the operation of said dressing device and the cessation of grinding on the workpiece, and means automatically operated by the cross-slide operating mechanism in retracting the cross-slide, following said cessation, for setting back said second member a predetermined distance in excess of said driving member. 105

10. In a cross-feed mechanism of the class described, a cross-slide, an actuating member therefor, means for progressively and automatically advancing said member, a second member adapted to advance with said actuating member, means operable by said second member for procuring cessation of the feeding movement of said cross-slide, a hand wheel operatively associated with said actu- 115 120 125 130

ating member and said second member, and means automatically operated on the retraction of said cross-slide by said hand wheel for producing a predetermined angular displacement between said actuating member and said second member.

11. In a grinding machine, a grinding wheel, mechanism for procuring a cross feed between said wheel and the workpiece, said mechanism comprising a cross-slide, an actuating member therefor, means for progressively and automatically advancing said member, a second member adapted to advance with said driving member, means operable by said second member for procuring cessation of grinding on said workpiece, a hand wheel operatively associated with said actuating member and said second member, and means automatically operated on the retraction of said cross-slide by said hand wheel, following said cessation of grinding, for producing an angular displacement between said actuating member and said second member.

12. In a cross-feed mechanism of the class described, a cross-slide, an actuating member therefor, means for progressively and automatically advancing said member, a second member adapted to advance with said driving member, means operable by the advance of said second member for procuring cessation of the feeding movement of said cross-slide, and a hand wheel operatively associated with said actuating member and said second member and adapted when operated for the retraction of said cross-slide to secure a predetermined angular displacement between said two members, there being a lost motion connection between said hand wheel and said actuating member.

13. In a cross-feed mechanism of the class described, a cross-slide, a member rotatable in opposite directions to secure, respectively, the feeding and withdrawal movements of said cross-slide, a second member rotating with said first member when the cross-slide is fed, devices directly set in operation by said second member on its arrival at a predetermined point adapted to procure cessation of said feeding movement, and means operable on the reverse rotation of said members, to withdraw said cross-slide, and automatically procure a predetermined angular displacement between them.

14. In a grinding machine, a grinding wheel, a mechanism for procuring a cross-feed between said wheel and the workpiece, said mechanism comprising a cross-slide, a member rotatable in opposite directions to procure, respectively, the feeding and withdrawal movements of said cross-slide, a second member rotating with said first member when said cross-slide is fed, devices directly set in operation by said second member on its arrival at a predetermined point adapted

to procure cessation of the grinding operation on said workpiece, and means operable on the reverse rotation of said members, following said cessation, to withdraw said cross-slide, and automatically procure a predetermined angular displacement between said members.

15. In a cross-feed mechanism of the class described, a rotatable actuating member, two other rotatable members operatively associated with said actuating member, friction means for restraining rotation of one of said members, a pawl and ratchet drive for the other of said members both from said actuating member and said frictionally restrained member, and means for moving said frictionally restrained member from said actuating member, after a predetermined lost motion between them, whereby to automatically change the relationship of said other member with respect to said actuating member, responsive to each double motion, clockwise and counterclockwise, of said actuating member.

16. In cross-feed mechanism of the class described, a feed screw, an actuating member for said feed screw, a pair of contact making devices, an element normally progressively advanced by said actuating member and adapted to successively actuate said contact making devices, and means responsive to withdrawal movements of said feed screw for changing the rotative relation of said element to said screw by a predetermined amount.

17. In mechanism of the class described, a feed screw, a driving element adapted when moved to turn said feed screw, a pair of contact making devices, a ring normally carried by said driving element and adapted to actuate said contact making devices, a hand wheel to withdraw said feed screw, and means, responsive to a withdrawal of said feed screw by said hand wheel to a given position of said feed screw, for changing the relative positions of said ring and said contact devices.

18. In mechanism of the class described, a feed screw, a driving element adapted when moved to turn said feed screw, a pair of contact making devices, a ring normally carried by said driving element and adapted to actuate said contact making devices, a hand wheel to withdraw said feed screw, and means, responsive to a withdrawal of said feed screw by said hand wheel to a given position of said feed screw, for changing the relative positions of said ring and said contact devices by a predetermined amount.

19. In mechanism of the class described, a feed screw, a driving element adapted when moved to turn said feed screw, a pair of contact making devices, a ring normally carried by said driving element and adapted to actuate said contact making devices, a hand wheel to withdraw said feed screw, and means, responsive to a withdrawal of said

- feed screw by said hand wheel to a given position of said feed screw, for changing the relative positions of said ring and said contact devices by a predetermined adjustable amount.
20. In a grinding machine, a grinding wheel, a feeding element which, when moved, causes said grinding wheel and a workpiece to approach or recede, a dressing device, means for moving said grinding wheel and dressing device, one relative to the other, in a line parallel to a geometrical element of the surface of said wheel, while maintaining the dressing device a fixed distance from the line of contact of said wheel and workpiece as hereinafter defined, thus to remove material from said grinding wheel, automatic means to move said feeding element, measuring means associated with said automatic feeding means to measure increments of said feed, the means for moving said grinding wheel and dressing device relatively being set in operation by said measuring means, whereby it may be caused to operate after preliminary grinding and at a point in the movement of said element which is advanced by a constant increment for successive grinding operations, means to cause the automatic feeding means to cease moving said element, said means being also actuated by said measuring means, said measuring means and the means to cause the automatic feeding means to cease operation being thus adapted to measure off a fixed movement of said element after causing said dressing operation, the aforesaid line of contact of said wheel and workpiece being defined at the moment said feeding means has last moved said element.
21. In the art of grinding a plurality of workpieces to the same size in a given dimension, the improvement which consists in determining approximately the amount of wear of a grinding wheel during each grinding operation, causing a grinding wheel to be advanced into contact with successive workpieces (and thereby cutting said workpieces) by an increasing amount for each successive workpiece, the increase being a constant one and being greater than the largest estimated possible wear of the grinding wheel, at that stage causing said grinding wheel to be made tangent to a known plane by dressing, said plane being located close to the desired finished surface locus of the workpieces and being relatively remote from the initial unground surface locus of the workpieces, and then causing the grinding wheel to be advanced by an always constant amount in cutting relation to the workpieces, which amount is greater than the lineal measure of the amount of reduction of the grinding wheel by the dressing device, such excess being equal to the difference between the estimated wear and the actual wear of the grinding wheel, and finally causing the grinding to cease at the end of the last named advance, thus producing accuracy in a series of grinding operations by measuring the finished surface from a dressing device located at a fixed point, said measuring being done just prior to completion of the grinding on a given article, leaving as the only variable the slight amount of wear of the grinding wheel during its short advance after dressing.

Dated this fourth day of August, 1925.
WALDO J. GUILD.
